DESIGN FOR A FISHING LURE

Benjamin H. Hatcher, Woodville, Tex.

Application May 17, 1944, Serial No. 113,629

Term of patent 14 years

(Cl. D31—4)

To all whom it may concern:

Be it known that I, Benjamin H. Hatcher, a citizen of the United States, residing at Woodville, in the county of Tyler and State of Texas, have invented a new, original, and ornamental Design for a Fishing Lure, of which the following is a specification, reference being had to the accompanying drawing, forming a part thereof.

In the drawing:

Fig. 1 is a top plan view of a fishing lure showing my new design.

Fig. 2 is a side elevation of the same.

Fig. 3 is a front elevation of the same.

I claim:

The ornamental design for a fishing lure, substantially as shown.

BENJAMIN H. HATCHER.
